CLAIM

The ornamental design for an organizer notebook, as shown and described.

DESCRIPTION

FIG. 1 is a perspective view of an organizer notebook showing my new design;

FIG. 2 is a top plan view thereof, in open condition showing the first divider portion;

FIG. 3 is a top plan view thereof, in open condition showing the second divider portion;

FIG. 4 is a top plan view thereof, in open condition showing the third divider portion; and,

FIG. 5 is a bottom plan view thereof.

The broken lines shown in FIGS. 2, 3 and 4 are shown for illustrative purposes only and forms no part of the claimed design.
